TOY SEAL

Iva E. Graupensperger, Altoona, Pa., assignor to James Industries, Inc., Philadelphia, Pa., a corporation of Pennsylvania

Application June 11, 1957, Serial No. 46,553

Term of patent 3½ years

(Cl. D34—2)

FIG.1.

FIG.3.

FIG.4.

FIG.2.

FIG.5.

Fig. 1 is a view in side elevation of a toy seal made in accordance with the present invention;

Fig. 2 is a view in plan of the toy seal shown in Fig. 1;

Figs. 3 and 4 are views in front and rear elevation, respectively, of the seal shown in Figs. 1 and 2; and,

Fig. 5 is a view in perspective of the toy seal in a position different from that shown in Figs. 1 to 4 inclusive.

I claim:

The ornamental design for a toy seal, as shown.
